United States Patent Office

Des. 215,751
Patented Oct. 28, 1969

215,751

COMBINED EYEGLASSES AND FLASHLIGHTS THEREFOR

Angelo Castellano, 2320 Spruce St.,
Tampa, Fla. 33607

Original design application July 17, 1967, Ser. No. 7,843,
now Patent No. 212,119, dated Aug. 27, 1968. Divided
and this application Mar. 14, 1968, Ser. No. 12,501

Term of patent 14 years

Int. Cl. D26—04

U.S. Cl. D48—24

FIG. 1

FIG. 2

FIG. 1 is an isometric view of combined eyeglasses and flashlights therefor embodying the invention;

FIG. 2 is a side elevational view of the embodiment disclosed in FIG. 1.

The dominant features of my design reside in the portions shown in full lines.

This is a division of design application Ser. No. D. 7,843, filed July 17, 1967, now Design Patent No. D. 212,119.

I claim:

The ornamental design for combined eyeglasses and flashlights therefor, as shown and described.
